COAT HOLDER

Daniel A. Hogan, Birmingham, Ala.

Application July 29, 1935, Serial No. 33,683

6 Claims. (Cl. 223—71)

My invention relates to a device for holding or setting coats, and particularly coats that have been laundered or dry cleaned and placed on coat hangers for delivery, so that they will not hang in folds and become creased but will retain their smoothly pressed condition indefinitely.

At the present time, where coats are laundered or dry cleaned, it is the general practice to button the coat after mounting it on a coat hanger and before inserting it in a paper bag for delivery. Coats, particularly of wash suits and of light summer goods, have a tendency to slip out of position on the smooth metal hangers customarily used and this tends to draw the coat out of shape and form wrinkles especially in the coat's front panels. It is further true as a general rule, particularly with light coats, that when buttoned their fronts will hang in folds from a flat hanger and get out of shape. I have conceived that these troubles can be corrected by devising some means which will permit the coat, after it has been mounted on a hanger, to be held in correct position on its hanger with its front panels left unbuttoned and lapped so that they will hang flat against each other free of folds. This requires that some device be applied which will hold the coat, with its front lapped, secure in position on the hanger and set so that it will reach the customer in unwrinkled condition.

I have conceived that such a device must be designed to interlock with the coat's lapels in such manner as not to indent or otherwise affect the smooth pressed or rolled appearance of the lapel.

To this end I have designed a coat holder or set which engages in the notch of the coat lapels and comprises a cross element which lies loosely over the lapels and inturned tabs which engage under the lapels to draw the coat front panels together and secure the holder in position on the garment.

My invention contemplates the provision of such a holder with one or more pairs of securing tabs adapted to engage under the collar on each side above the notch.

My invention further contemplates rounding the upper corners of the holder so that they will not offer any obstruction on which the bag will hang as it is slipped down over the finished garment on the hanger.

My invention further contemplates cutting the holder of cardboard so that it can be very inexpensively produced and at the same time it will provide an excellent advertising display space on the cross band that loosely overlaps the lapels.

My invention further comprises the novel de-

tails of construction and arrangement of parts which in several embodiments are illustrated in the accompanying drawing which forms a part of this specification, and which is hereinafter more particularly described.

According to the drawing:—

Fig. 1 is a view of my invention applied to a coat ready for insertion in a bag.

Fig. 2 is a detail view of the form of holder shown in Fig. 1.

Fig. 3 illustrates a modification of the holder which is the preferred form.

Fig. 4 is a further modification of the simplest embodiment of my invention.

Similar reference numerals refer to similar parts throughout the drawing.

In the embodiment of my invention illustrated in Figs. 1 and 2, I show a coat 5 mounted on a hanger 6 and on the point of being placed in a paper bag 7 such as is in general use to protect dry cleaned or laundered garments.

Where the garment is a coat, the practice has been to button it after mounting it on its hanger, but such buttoned garment will not hang flat but its front will fall into folds which form wrinkles. Where such garments are hung so as to be pressed together, as in the delivery wagon or truck, or on the hanger racks in the dry cleaner's establishment or laundry awaiting delivery, or even in the customer's closet, such folds in the front become quickly set and the garment loses its neatly pressed effect.

I propose to set the garment on its hanger so that it will hang flat and will be held against any tendency to fall into folds and thus become creased. To this end I use a holder 8 of cardboard, or like light stiff inexpensive stock, which is cut to provide a cross band 9 adapted to overlie the lapels 10 and be held in engagement with them by the provision, on each side, of an inwardly projecting bottom flap 11 adapted to be slipped under a lapel and a top tab 12 adapted to engage under the coat collar 13.

The side edges of the holder taper symmetrical-
ly to the bottom edge of its flaps 11, the inner
edges 13 of which flare apart upwardly at an
angle which roughly conforms to the pitch of
its respective lapel, as these edges engage the
fold of the lapels. Each edge 13 merges at its
upper end into a transverse notch 14 which de-
fines the upper edge of its respective flap and
spacess it sufficiently from the cross band 9 to
avoid any tendency to pinch or press on a lapel
when in position between a flap and said band.

Each top tab 12 is defined by a notch 15 that

spaces it from the cross band 9 and avoids any tendency to pinch or press on the collar 13 in position between it and said band.

It will be noted that the upper corners of the holder 8 and flaps 11 are rounded as are the inner ends of the notches 14 and 15 and the tip of each tab 12, thereby eliminating any part to catch on the bag 7 as it is lowered over the garment or to pinch or press against the garment.

- 10 In use, the coat is left unbuttoned on the hanger 6 and its front portions are lapped and hang flat and straight without folds or creases. The holder 8 is then applied, the lapels being slipped into the notches 14 in position opposite the V-notch between the collar and lapels with the flaps 11 engaged under the lapels and the tabs 12 caught under the collar. Thus placed the cross band lies lightly and freely across the lapels without pressing on or indenting them and by 15 means of the opposed spaced flaps 11 engaging the fold of the lapels they are held in set position. The V-notches of the collar and the tabs prevent the holder working up or down so that it will hang lightly in set position while the garment is being bagged, transported and suspended in the customer's closet, keeping the coat front in as perfect condition as when it left the presser.

15 In Fig. 3 I show the preferred embodiment of my invention. Here the holder 18 is similar to 30 8 except that I extend its side edges higher so I can provide two pairs of tabs 19 and 20, the notches 21 between the tabs being extended beyond the notches 15 to adapt the holder for use with wider collars than can be fitted into the 35 shorter spaced notches 15.

20 In Fig. 4 I show the most inexpensive form of my invention in which the holder 28 is similar to 30 8 except all tabs are omitted and the top edge of the cross band 9 merges in a curve into the 40 side edges of the holder. Here the holder must rely on its flaps 11 to hold its cross band supported in the V-notches of the lapels.

25 While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior 35 art or as are specifically set forth in the appended claims.

30 What I claim is:—

1. A holder for the front of a coat, with lapels, hung on a coat hanger, comprising a body having 45 flaps adapted to be engaged under the free edges of the lapels of the coat when its front sections 50

are unbuttoned and overlapped to hang smooth and flat, and a cross band connecting said flaps, there being an inwardly opening notch between each flap and said band in which the V-notch of a lapel is adapted to be received.

2. A garment holder, comprising a body of stiff material having therein a T-shaped notch opening through its bottom and forming a pair of flaps spaced from each other and from the top portion of the body which connects them and which are adapted to be engaged under the free edges of garment lapels to hold same in predetermined relative position.

3. A garment lapel holder, comprising a body of sheet cardboard having a cross band and below it a pair of opposed inwardly directed spaced flaps adapted to engage under lapels that are overlaid by said band, there being a notch to free and space the upper edge of each flap from said cross band and permit the inner edges of 20 the flaps to engage the lapel fold.

4. A garment lapel holder consisting of a flat cardboard body cut out to provide a cross band, long enough to overlie and extend beyond the lapels of the garment, and a flap at each end of the band joined thereto and spaced in position for the free inner edges of said flaps to be engaged under the free outer edges of the garment lapels, a pair of opposed inwardly extending spaced collar engaging tabs above said cross band.

5. A garment lapel holder consisting of a flat cardboard body cut out to provide a cross band, long enough to overlie and extend beyond the lapels of the garment, and a flap at each end of the band joined thereto and spaced in position for the free inner edges of said flaps to be engaged under the free outer edges of the garment lapels, a pair of opposed inwardly extending spaced collar engaging tabs above said cross band, there being a notch to free and space the lower edge 40 of each tab from said cross band.

6. A garment lapel holder consisting of a flat cardboard body cut out to provide a cross band, long enough to overlie and extend beyond the lapels of the garment, and a flap at each end of the band joined thereto and spaced in position for the free inner edges of said flaps to be engaged under the free outer edges of the garment lapels, two pairs of opposed inwardly extending spaced collar engaging tabs above said cross band, there being notches to define and space adjacent tabs and the closed outer ends of one opposed pair of tab spacing notches being spaced further apart than the closed ends of the other opposed pair of tab notches.

DANIEL A. HOGAN.
